UNITED STATES PATENT OFFICE.

FRANK G. KOEHLER, OF ST. LOUIS, MISSOURI.

AUTOMATIC COUPLING.

1,302,931.

Specification of Letters Patent.

Patented May 6, 1919.

Application filed March 27, 1917. Serial No. 157,645.

To all whom it may concern:

Be it known that I, FRANK G. KOEHLER, a citizen of the United States of America, a resident of the city of St. Louis, State of Missouri, have invented certain new and useful Improvements in Automatic Couplings, of which the following is a full, clear, and exact description, reference being had to the accompanying drawings, forming a part of this specification.

My invention relates to improvements in automatic couplers, the main object being to produce a strong, simple and reliable automatic coupling device for trucks and other vehicles.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a fragmentary plan view of a train of trucks equipped with automatic couplers constructed in accordance with my invention.

Fig. II is an enlarged plan view showing the end portions of two trucks and the coupling device whereby the trucks are connected.

Fig. III is a section taken approximately on the line III—III, Fig. II, showing the knuckle in its closed position.

Fig. IV is a vertical section showing the knuckle in its open position.

Fig. V is an end view showing the knuckle in its closed position.

Fig. VI is a vertical section taken approximately on the line VI—VI, Fig. III.

Fig. VII is a detail view of the connecting link.

Each truck A of the train shown in Fig. I is provided with a connecting link B at one end, and a coupling head C at its opposite end. When a link B of one truck is forced into the head C of another truck, a knuckle is thrown to its closed position and automatically locked so as to couple the two trucks together.

Each coupling head is preferably secured to the end of a truck by means of bolts 1. A knuckle D, arranged between wings 2 which

extend downwardly from the connecting head, is pivotally supported by a horizontal pivot pin 3 passing through a hub 4 on the knuckle, and also through the wings 2. The coupling head has a flaring mouth 5 for the reception of the connecting link B. The knuckle comprises a substantially L-shaped coupling hook 6 extending forwardly and upwardly relative to the horizontal axis of the pivot pin 3, a striking member 7 (Figs. III and IV) having a striking face 7', an arcuate friction face 8 adapted to be engaged by a latch device L, and a pair of abutments 9 (Figs. III, IV and VI) adapted to coöperate with said latch device. The top wall of the flaring mouth is slotted at 10 to receive the upper portion of the striking member 7, and the bottom wall is slotted at 11 to receive the coupling hook 6.

When the knuckle occupies its open position (Fig. IV) the striking member 7 extends entirely across the flaring mouth 5 of the coupling head, so that its striking face 7' may be engaged by the end of a link B to throw the knuckle to the closed position shown in Fig. III. When the knuckle is closed its coupling hook 6 extends across the flaring mouth 5 and interlocks with the link B (Figs. II and III).

The gravity latch device comprises a vertically movable latch member slidably fitted to the head C and provided with a pair of legs 12 (Figs. III and VI) which lie directly in front of the abutments 9 when the knuckle occupies its closed position. When the knuckle is open the lower ends of these legs rest upon the arcuate friction surfaces 8, as shown in Fig. IV. When the knuckle is thrown to its closed position, the latch device drops by gravity from the position shown in Fig. IV to the position shown in Fig. III where it will coöperate with the abutments 9 to lock the knuckle. The legs 12 of the latch device then straddle a portion of the knuckle, as shown most clearly in Fig. VI. The bottom faces of the legs 12 (Figs. III and IV) are preferably wedge-shaped to allow the gravity latch to drop freely in front of the abutments 9 when the knuckle is thrown to its closed position.

One of the legs is provided with an extension 12' having a transverse retaining arm 14 which extends through an opening in the knuckle (Figs. III, IV and VI) to secure the latch device to the knuckle. An unlocking lever 15, extending into a loop at the upper

- end of the latch device L, is pivotally supported at 16. When the unlocking lever is operated to lift the latch device, the knuckle will drop by gravity to the position shown 5 in Fig. IV, thus releasing the coupling hook 6 from the link B. The coupling hook 6 is so heavy that it overbalances the weight of the other elements of the knuckle and causes the knuckle to move about its horizontal axis 10 to the open position shown in Fig. IV when the latch device is elevated. The movement of the knuckle is limited by the transverse retaining arm 14 of the latch device, as seen in Fig. IV.
- 15 The knuckle D and latch device L may be detached from the head C by removing the horizontal pivot pin 3 and permitting said knuckle and latch device to drop by gravity from the head.
- 20 The connecting link B is preferably a continuous loop pivotally mounted in bearings 17 and provided with an offset portion 18 which lies between the bearings 17 (Fig. VII). The axis of the bearings 17 is horizontal, and the link B can swing freely on said axis without transmitting injurious shocks to any part of the coupling device. This allows the train of trucks to be pulled over a rough floor or roadway without injuring the coupling elements. A leaf spring 19 fitted to the offset portion 18 of the link B, normally tends to retain said link in the operative position shown in the drawings. When the link occupies its operative position 25 it extends forwardly from its pivotal support, but when not in use it may be shifted to extend backwardly from said pivotal support, as suggested by dotted lines in Fig. III. It will be noted that the leaf spring 19 is 30 adapted to coöperate with the offset portion 18 of the link to retain the latter in the position to which it is shifted.
- The outer end portion of the link B lies in 35 the coupling head C and is subjected to bending stresses and also becomes worn by frictional engagement with the coupling hook 6 and other elements of the device. This part of the link is, therefore, enlarged, as shown in Figs. II and III.
- 40 When the latch device L is lifted to open the knuckle, the transverse arm 14 at the

lower end of the latch device (Fig. III) engages a cam face 20 to impart an initial or starting impulse to the knuckle. This releases the knuckle quickly and prevents it 55 from being retained by friction in its closed position.

Abutment lugs 21 (Figs. III and V) are formed at the inner end of the flaring mouth 5 on opposite sides of the striking member 7 60 to receive the inward thrusts of the link B. These lugs 21 also serve as abutments for the latch device L, the pulling stresses being transmitted from the link B to the coupling hook 6, thence through the arcuate rear portion of the knuckle to the lugs 9, latch device L and lugs 21.

I claim:

1. An automatic coupler comprising a head, a knuckle pivoted to said head, and a 70 gravity latch device slidably fitted to said head, said gravity latch device having a pair of legs adapted to straddle a portion of said knuckle when the latter occupies its closed position and the knuckle being provided with 75 a pair of abutments adapted to engage said legs to lock said knuckle in its closed position.

2. An automatic coupler comprising a head, a knuckle pivoted to said head, and 80 an automatic latch device for securing the knuckle in its closed position, said knuckle having an opening and the automatic latch device being provided with a retaining finger which extends into said opening to secure the 85 latch device to the knuckle.

3. An automatic coupler comprising a head, a knuckle pivoted to said head, the axis of the pivot being horizontal, a gravity latch device coöperable with said knuckle to lock 90 the latter in its closed position, said knuckle having a friction face upon which the gravity latch device is supported when the knuckle occupies its open position, and said gravity latch device having a horizontal retaining 95 finger which extends into said knuckle at a point below said friction face to secure the latch device to the knuckle.

In testimony that I claim the foregoing I hereunto affix my signature.

FRANK G. KOEHLER.
